UNITED STATES PATENT OFFICE

FRANK L. ROUSSEAU, OF CHICAGO, ILLINOIS

SAFETY-PACK HOLDER

Application filed December 22, 1926. Serial No. 156,501.

My invention relates to an improved safety pack holder, and more particularly to a type of holder having the combined function of holding in one end a pencil or other writing means, and providing in its opposite end a storage space which is adapted to contain a safety pack.

My invention relates further to an improved holder of the type above described, provided with means engaging the contained safety pack holding the pack against accidental outward movement, and for engaging the side of the pack when the pack is removed from its container to rip the envelope or wrapper surrounding the elements constituting the pack so that the elements may be available for use immediately upon removal.

The value of this invention resides in its simplicity and convenience in removing the safety pack from its holder and its accessibility and handiness realized by combining the safety pack holder with a holder for a pencil or other writing means or any other article that is usually carried on the person and which is readily available at times of emergency or at unexpected moments when need for its use arises. It is usually true that one carries at all times for convenient use a pencil or writing element of some description, and especially in factories or any other locations where workmen are subjected to dangers or liability of being injured by cuts and bruises or the like, where emergency packs of this type will be of great service. It will be readily seen, therefore, that a very convenient, useful and desirable combination is effected, and one which will readily render valuable service by combining a holder containing an article that is usually carried on the person, and providing a storage space for an emergency pack in said holder.

One of the objects of my invention is to provide a holder having storage space in one end adapted to contain a safety pack either directly positioned in the end of the holder and retained therein by a suitable cap positioned thereover, or to contain a cylindrical cartridge enclosing a safety pack which will serve as a cap for the end of the holder and which may be removed from the holder so

that the pack in turn may be removed from it.

Another object of my invention is to provide a holder in combination with a pencil or other means as above described which is provided with a storage space either in one end of the main body portion of the holder or in a cartridge as described in the above stated object, the portion of the container enclosing the safety pack being provided with an inclined edge surface and a projecting overhanging lip which serves to engage the end of the safety pack in inserted position to hold the pack against accidental outward movement, and to further act as a cutting means for the envelope or wrapper of the pack, usually of paper, when the pack is removed from its holder to release the elements constituting the pack to render them readily available for use. The inclined edge of the holder provides a means for readily gripping the exposed portion of the pack between the fingers so that it may be readily withdrawn.

These and other objects are accomplished by means of the arrangement disclosed on the accompanying sheet of drawings, in which—

Figure 1 is a side elevation of a pencil and holder constructed in accordance with the principles of this invention;

Figure 2 is an enlarged cross sectional view of the form of my invention shown in Figure 1, the pencil being in reverse position, enclosed as when not in use, the safety pack being contained in a cartridge insertable into and carried in the opposite end of the holder;

Figure 3 is a view similar to Figure 2 of a modified form of my invention in which the safety pack is contained in the end of the main body portion of the holder, the end of which is enclosed by a suitable cap; and

Figure 4 is a perspective view of the cartridge and safety pack of the type shown in Figure 2, the pack being shown partly removed to reveal the operation and effect of the projection on the casing in ripping the envelope enclosing the elements constituting the pack.

The various novel features of the invention will be apparent from the following descrip-

tion and drawings and will be particularly pointed out in the appended claims.

Referring to the drawings, it will be noted that my invention comprises a holder 10 formed of suitable material of tubular shape and preferably, but not necessarily, provided with a shoulder 11 in a restricted end portion 12, which serves to hold a suitable writing means, such as pencil 13. The pencil is held in a cap member 14 provided with a ridge 15 and is adapted to be positioned with the end of the pencil exposed, as shown in Figure 1, or in a closed position as when carried in the pocket when not in use, as shown in Figure 2. In either instance, the portion of the tube 12 engages the cap 14 to hold the pencil in place, the ridge 15 forming a stop to limit the degree of insertion in either position. As shown in Figure 2, the opposite end of the holder 10 receives a cartridge member 16, the inward movement of which is limited by the shoulder 11 in the holder so that the pack and the pencil point are always maintained in spaced relationship.

The pack 17 preferably comprises a roll of gauze 18, and a small roll of adhesive tape 19, the gauze having sewed thereto a mercurichrome pad, but it is to be understood that the pack may be of any suitable type depending upon the treatment desired under given conditions, the kind selected being that suitable for treating expected or likely emergencies. The elements comprising the pack are enclosed in a suitable wrapper 20, preferably of paper or any material which may be readily severed, the wrapper serving to maintain the elements of the pack clean and in a thoroughly sterilized condition.

The cartridge 16 is provided at its inward end with an inclined end wall 21 and a projection 22 having a sharp point adapted to engage the side of the pack when it is withdrawn from the cartridge in a manner to rip the wrapper to release the elements of the pack. The projection 20 further serves as a retaining means for the pack within the cartridge to prevent the cartridge from accidental outward movement.

The modification shown in Figure 3 embodies the same principles, it being different in structure only in that the pack 17' is contained directly within the body portion of the holder 10' in a storage space embodied between the end of the holder 10' and the shoulder 11'. In this instance, the end of the holder is provided with a cut-away portion 21' and the projection 22' serves in the same manner as the corresponding elements of the cartridge in Figure 2. In this form, a cap member 23 is provided to closely engage the outer surface of the holder 10' and to close the end thereof.

In operation, in the event of an emergency, it is merely necessary to remove the cartridge from the end of the holder, to grasp

the projecting end of the pack and to withdraw it as shown in Figure 4, during which operation the wrapper for the pack is ripped to release the elements for immediate use.

I claim:

1. The combination of a holder having a storage space in one end thereof, and a safety pack in said storage space, said holder having a projection engaging the side of said pack upon removal to rip the wrapper thereof.

2. The combination of a holder having a storage space in one end thereof, and a safety pack in said storage space, said holder having a projection engaging said pack to hold said pack against accidental outward movement and for engaging the side of said pack upon removal to rip the wrapper thereof.

Signed at Chicago, Illinois, this 13th day of December, 1926.

FRANK L. ROUSSEAU.
